Primary Examiner — Sheryl Lane*Assistant Examiner* — Mark T. Philippss(74) *Attorney, Agent, or Firm* — Kinney & Lange, P. A.(57) **CLAIM**

The ornamental design for a fluid head retainer, as shown and described.

DESCRIPTION

FIG. 1 is a perspective view of a fluid head retainer;
 FIG. 2 is a front elevational view of the fluid head retainer;
 FIG. 3 is a rear elevational view of the fluid head retainer;
 FIG. 4 is a right side view of the fluid head retainer;
 FIG. 5 is a left side view of the fluid head retainer;
 FIG. 6 is a top plan view of the fluid head retainer; and,
 FIG. 7 is a bottom plan view of the fluid head retainer.
 The broken lines in the Figures represent portions of the fluid head retainer and form no part of the claimed design.

1 Claim, 7 Drawing Sheets(56)
